UNITED STATES PATENT OFFICE.

LE ROY B. FRASER, OF NEW HAVEN, CONNECTICUT.

METHOD OF FINISHING SPINNING RINGS.

Application filed June 11, 1920. Serial No. 388,286.

To all whom it may concern:

Be it known that I, LE ROY B. FRASER, a citizen of the United States, residing at New Haven, in the county of New Haven 5 and State of Connecticut, have invented a certain new and useful Improvement in Methods of Finishing Spinning Rings, of which the following is a full, clear, and exact description.

10 This invention relates to a method of finishing spinning rings, and is particularly adaptable to spinning rings of sheet metal of the type disclosed in application Serial No. 346,402, filed December 20, 1919, 15 covering a process of producing such rings.

Spinning rings of sheet metal of the general type referred to in the application above mentioned have many advantages, 20 from a practical as well as an economical standpoint, over spinning rings which are formed of cast metal. Sheet metal spinning rings, however, are more or less liable to distortion, which interferes seriously with 25 the performance of their functions, and accordingly it has been considered necessary to subject these rings to some hardening process, whereby they will maintain their shape, both during the process of manufacture and the subsequent use of the ring in 30 the performance of its usual functions.

Spinning rings of sheet metal are, in addition to the hardening process, subjected 35 ordinarily to a polishing process which imparts to the surfaces of the ring a higher finish, thus adding to the appearance of the ring, and additionally presenting to the traveler a smooth and polished surface, which results in reducing the friction between the traveler and the ring, and thereby increases the speed of the traveler which 40 is the desirable result in spinning.

The present invention has for one of its important objects an improved method of 45 finishing spinning rings of the type referred to, and of other types, through a series of steps which effects the polishing of the ring in a highly efficient manner.

50 Preferably, the ring, during an intermediate stage of its manufacture, and before the flange is bent into the required relation to the base of the ring to form an inclined raceway, is successively subjected to the action of suitable polishing tools to

remove all scratches and defects from the 55 ring. The polishing steps occur prior to hardening and while the metal is in a relatively soft state. Thereafter, the ring is subjected to the hardening process which 60 renders it stiff and capable of maintaining its required shape, and subsequently to such hardening the ring is subjected to a further polishing operation, known as the 65 "hard polishing" which imparts a high finish to the ring, and completes its manufacture. By proceeding in the order of steps herein enumerated, the ring may be polished very successfully, and the inner and outer faces of the raceway flange and the 70 upper surface of the base of the ring, will receive a high gloss or polish, which experiments have shown to be of a superior quality.

In the drawings, which illustrate, by way of example, one form of apparatus for carrying into effect certain steps of the process:

Figure 1 is a view in side elevation of a polishing pad, and one form of block or holder therefor, together with the driving spindle and frame for supporting the parts;

Figure 2 is a view, in end elevation, of the pad and holder, taken from the left hand side of Figure 1;

Figure 3 is a vertical sectional view of the pad and holder, shown in Figs. 1 and 2, together with the driving spindle;

Figure 4 is an end elevation, and

Figure 5 is a sectional view, of a modified form of holder for an abrasive pad;

Figure 6 is a sectional detail view of a 90 partially formed spinning ring, in condition to be subjected to the polishing process;

Figure 7 is a sectional detail view of the ring, completely finished as to its form by the bending of the flange into angular relation to the base;

Figure 8 is a longitudinal sectional view of a chuck for holding the ring in position for polishing, together with the polishing pad and its holder; and

Figure 9 is a side-elevational view of the chuck shown in Figure 8.

In manufacturing sheet metal spinning rings of the type described in the application above referred to and as shown in Figure 7 105 of the drawings of the present application, a sheet metal blank is subjected to the action of suitable dies, which press the blank,

through successive stages, into the form of a finished spinning ring which comprises a base portion 21, and an inclined flange 22 constituting a raceway for the traveler. As 5 heretofore explained, spinning rings of this type should be subjected to a suitable hardening process to enable them to maintain their shape under all conditions of manufacture and use. Under the present process, 10 the blank from which a ring is to be formed is brought, by successive stages, into the condition shown in Figure 6 of the drawings, wherein the flange 22, which is subsequently bent into such relation of the base as to form 15 an inclined raceway, extends at right angles to the base. While the flange extends in such relation to its base the top of said base and the face of flange 22 towards the base are "soft polished" by presenting these surfaces 20 to a suitable pad of felt, or similar material, carrying on its surface an abrading material, sufficiently coarse to remove all scratches, etc. The ring is then flared, as shown in Fig. 7, and the under surfaces of 25 the base 21 and the folded edge are "soft polished." After being so treated, the ring is hardened, and its top, bottom, and folded portions are presented to a polishing pad whose surface carries an abrasive material 30 which is preferably finer than that used during soft polishing, to bring out the necessary finish.

Referring to Figure 1 of the drawings, which illustrates one form of apparatus for 35 applying the abrasive material to the surface of a ring, a suitable base 14 carries standards 10, 12, which sustain bearings for a rotatable spindle 7, having thereon fast and loose pulleys 9, 9'. One end portion of 40 the spindle 7, passes through, or is otherwise rigidly secured to a block 1 of wood, or of layers of leather. This block is provided with an annular recess which receives a ring 3 of felt, or other suitable material, to the 45 outer face of which is applied the abrasive material for polishing the ring. Under one proposed method of procedure, the ring is held in contact with the face of the pad 3, while such pad is rotated at a high speed, 50 through suitable power applied to the pulley 9, and the flange 22 of the ring will either form a circular groove 5 in the face of the pad 3, or will enter a previously formed groove therein, and the face portion of the 55 felt pad and the walls of the groove will engage and polish the surfaces of the flange 22 and base 21.

Under another form of the invention, the 60 spindle 7 for the pad carrying the abrasive element has secured to its end a disk 7^a, which is provided with an annular recess to receive the felt pad 3. Adjusting screws 17 engage an annular plate or washer 20 at their inner ends, and serve to move the pad 65 3 forward the required distance to cause

said pad to bear firmly against the surface of the ring to be polished, the screws 17 affording means to adjust the pad to compensate for the wear upon its outer face. Suitable nuts 18, 19, are provided for the purpose of imparting movement to the screws 17 and for locking such screws in adjusted position.

In Figures 8 and 9 of the drawing is illustrated a chuck which is particularly constructed for holding a spinning ring of the character shown in Figure 6, and of presenting such ring to the polishing pad 3, which is carried by the holding block 1 at the end of the spindle 7. The numeral 28 represents the spindle of a lathe, which spindle is provided near one end with external screw threads 30, which engage internal threads of a contracting chuck member 32, whose outer face is provided with a recess, 35 whose outer wall is beveled, as indicated at 33. An inner contracting member 34, is received within the recess formed in the face of the member 32, the contracting member 34 being provided with a plurality of radial slits 40, and said contracting member having a stem portion 24 which is formed tapering at 26, to engage an inner tapering surface formed at the end of a recess in the spindle 28. The outer face of 40 the chuck member 34 is provided with a counter-sunk groove 41, within which is seated the base portion 21 of the spinning ring to be polished. By turning the chuck member 32 upon the threads 30 in a direction to cause said member to move towards the right in Figure 8, the tapering surface 33 will engage the outer tapering face 36 of the chuck member 34, thereby contracting said member so that it will be caused to grip 45 the periphery of the base 21 of the ring, thereby holding the ring firmly during the polishing process, so that the centrifugal force which is imparted to the ring, due to the high rotation of the spindle 28, does not 50 force the chuck to expand and permit the ring to be disengaged from said chuck.

With the construction illustrated in Figure 8, the spindle 28 of the lathe is rotated at a high speed, thereby rotating the ring 55 while in engagement with the polishing pad 3. At the same time, if desired, the spindle 7 carrying the polishing pad may also be rotated at a suitable speed and in a direction which is opposite to the direction of 60 rotation of the ring, and by rotating the ring and pad in opposite directions a high 65 polish may be imparted to the ring, in a very short time.

It will be understood that changes may be 70 made in the details of construction or in the relative arrangements of the parts of the apparatus herein shown and described, and furthermore that the process may be carried out, as to the polishing steps, by 75

other forms of apparatus than those herein disclosed.

What is claimed is:

1. The method of finishing spinning rings, which comprises partly forming a ring with a base and an angularly projecting raceway flange, subjecting the partly formed ring to the action of a polishing member for removing the scratches and defects, suitably hardening the ring, and thereafter subjecting said ring to a second polishing process.

2. A method of finishing spinning rings, which comprises partly forming a ring of sheet metal with a base and an angularly projecting raceway flange, preliminarily subjecting certain portions of such ring to the action of a polishing member, bending said flange at an acute angle to said base,

thereafter polishing other portions of the ring then subjecting the ring to a suitable hardening process, and finally subjecting the rings to another polishing action to impart a finish to its surface.

3. The method of finishing spinning rings of sheet metal which comprises, partly forming a ring with a base and an upstanding raceway flange, subjecting certain parts of such partly formed ring to a preliminary polishing process to remove the defects from the surface of the ring, bending the raceway into an inclined relation to the base, suitably hardening the ring to enable it to maintain its shape, and thereafter subjecting the ring to a finishing polishing operation.

In testimony whereof I have hereunto set my hand this 26th day of May A. D. 1920.

LE ROY B. FRASER.
